UNITED STATES PATENT OFFICE.

STEPHEN A. MARKER, OF INDIANAPOLIS, INDIANA.

IMPROVEMENT IN HARNESS-SADDLES.

Specification forming part of Letters Patent No. 147,509, dated February 17, 1874; application filed October 2, 1873.

To all whom it may concern:

Be it known that I, STEPHEN A. MARKER, of Indianapolis, in the county of Marion and State of Indiana, have invented certain new and useful Improvements in Combination Braces and Loops for Harness-Saddles, &c.; and I do hereby declare the following to be a full, clear, and exact description of the invention, such as will enable others skilled in the art to which it pertains to make and use it, reference being had to the accompanying drawings, which form part of this specification, and in which—

Figure 1 is a top view of a skirt having my improved combination brace and loop. Fig. 2 is a side view of the same. Fig. 3 is a bottom or rear view of the same, showing the spring and its mode of attachment to the skirt; and Fig. 4 is a view of the combination brace and loop detached from the skirt and jockey.

Similar letters of reference indicate corresponding parts in all the figures.

My invention has for its object to produce a combination brace and loop for harness-saddles, in which a metallic spring is secured to the leather skirting by a bolt which forms a part of the metallic brace and loop, cast in one piece, as hereinafter described.

By reference to the drawing it will be seen that A is the skirt, and B is the jockey or housing, stitched on three sides, at b, b, and b, to the skirt, but having a blind stitching at the lowermost side, b', so as to form a pocket or receptacle for the shank C of the brace. This shank, as seen in Fig. 4, has a hole, c, which, when the brace is placed in position on the skirt, between that and the jockey, will correspond with the two perforations a and d, the former of which is in the jockey B, and the latter in the skirt A. Through the hole thus formed, by corresponding perforations in the jockey, brace, and skirt, I pass the terret-bolt, which is fastened by means of a nut in the harness plate or pad, in the usual way, and thus serves to securely unite the shank of the brace to the skirt. D is the stem, and E is the loop, of my combination brace and loop.

The stem is preferably corrugated, as shown;

or it may be of any other pattern, pretty and attractive, without detracting from its strength, so as to dispense with the necessity of covering it with leather.

The shank C, stem D, and loop E, are all made in one casting, of iron, steel, or any other suitable metal, and may be japanned, so as to imitate leather; or it may be gilt, plated, or ornamented in any other suitable way.

The lower portion of the stem, just above the loop, is provided with a bolt, e, on the under side, which passes through a corresponding hole in the skirt, and also through a corresponding perforation in the spring F, which latter is placed on the under side of the leather skirting A, and held in place by the bolt e (which forms a part of the said loop and brace) and nut f, as shown in Figs. 2 and 3. This spring keeps the lower portion of the skirt in proper shape, and acts also as a brace, giving it additional strength and elasticity. It also prevents the nut f from wearing on the leather. It is made of metal, preferably steel, and is securely held in place by the bolt e and flanged nut f. The two flanges of the latter are perforated, as shown in Fig. 3, so that it may be tacked onto the under side of the skirt, and thus prevented from turning or working loose.

By securing the spring F to the leather skirting by the bolt e, which forms a part of the loop and brace proper, in the manner shown, I obtain simplicity of construction, coupled with great solidity and strength.

I therefore claim as my invention, and desire to secure by Letters Patent—

The combination of the spring F, leather skirting A, and metallic brace having the bolt e formed as a part thereof, substantially as described.

In testimony that I claim the foregoing I have hereunto set my hand this 26th day of September, 1873.

STEPHEN A. MARKER.
